United States Patent Office

Des. 215,144
Patented Sept. 9, 1969

215,144

PULL TAB

Herman R. Markert, Hartsville, S.C., assignor to Sonoco Products Company, Hartsville, S.C., a corporation of South Carolina

Filed Mar. 1, 1968, Ser. No. 10,804

Term of patent 14 years

The portion of the term of the patent subsequent to Apr. 30, 1982, has been disclaimed

Int. Cl. D9—02

U.S. Cl. D9—256

Fig. 1

Fig. 2

Fig. 3

I claim:

The ornamental design for a pull tab, substantially as shown.
